UNITED STATES PATENT OFFICE.

WILHELM GRAAFF, OF BERLIN, GERMANY.

CHEMICAL FIRE-EXTINGUISHER WITH EXPANSION DEVICE MOUNTED ON THE DISCHARGE-PIPE.

No. 920,454.

Specification of Letters Patent.

Patented May 4, 1909.

Application filed July 25, 1906. Serial No. 327,766.

To all whom it may concern:

Be it known that I, WILHELM GRAAFF, merchant, a subject of the German Emperor, and a resident of Potsdamerstrasse 10-11, 5 in the city of Berlin, in the Kingdom of Prussia and German Empire, have invented a certain new and useful Chemical Fire-Extinguisher with an Expansion Device Mounted on the Discharge-Pipe, of which the following is a specification.

An inconvenience frequently met with in chemical fire extinguishers, for instance in those of the so-called Minimax-type is the fact, that in view of the necessity of providing a certain air space on top of the liquid constituting the contents of the apparatus, the liquid is very often forced upward into the discharge pipe in the inoperative position of the apparatus on account of expansion of the inclosed air by heat or by some evolution of gas, such liquid being then capable of escaping to the outside from the discharge pipe by the ejection nozzle. This so-called "working" of the fire extinguisher is particularly to be feared in countries with tropical heat, but aside from this, there are other chances of all the causes coöperating together which result in the undesirable discharge of liquid from the nozzle. Various means have been tried, to remedy this difficulty; by making use of boiled or highly heated water for the filling of the apparatus, its property of subsequently evolving gases may be diminished, inasmuch as the gases are thereby made to escape. Another means against this working action of the apparatus consists in providing capillary vent holes on the discharge pipe and above the level of the liquid; this remedy is however very impracticable, because it is impossible to keep these discharge holes from getting choked up after awhile, and furthermore on account of the fact that the ejecting pressure and the length of throw of the ejected jet are interfered with in the employment of the fire extinguisher by the blowing off at these holes.

This invention is based on the fact, that the most simple remedy afforded against these difficulties is, to provide a shoulder or crank shaped part or an enlargement in the discharge pipe above the water level, whereby an ample collecting space is provided, into

which the liquid rising in the discharge pipe, is discharged in the first place, so that the escape of the liquid from the nozzle is practically excluded. It has however been found, that the arrangement of an intermediate enlarged chamber of this kind directly at the discharge pipe will result in the inconvenience, that the force of the ejected jet is considerably interfered with by this kind of chamber which constitutes an interruption of the continuity of the discharge pipe; the jet, which is ejected by the pressure of the carbonic acid actually meeting with a kind of stop or resistance in the interior of the discharge pipe by the liberation of quantities of carbonic acid, temporarily evolved in the enlarged part, so that the jet escapes with a cracking noise and without the desired continuity of the liquid, while at the same time the length of throw is diminished. In view of this state of facts, the present invention is characterized by the fact that a discharge pipe of unaltered continuity is connected with a laterally mounted expansion chamber the interior of which communicates with the interior of the pipe by means of one or two small holes in the wall of the same and which constitutes a free space for the collection of liquid above the level of the liquid.

Upon the accompanying drawing an arrangement corresponding to the principle of this invention and applied to a Minimax-extinguisher of well-known construction, is shown by way of example.

Figure 1 represents the fire extinguisher with the discharge pipe, provided with an expansion chamber, in sectional view; Fig. 2 is a cross section on the line A—B, which line may also indicate the height of the level of liquid at the interior of the fire extinguishing apparatus.

Up to this height approximately which will still leave in the upper part of the apparatus a column of air of, say 25 centimeters, the Minimax-receptacle *a* is filled with the solution of carbonate of soda. The discharge pipe *b* is arranged alongside of the receptacle; it is preferably of oval cross-sectional shape and extends with a cone-shaped part from the lower and wider entrance opening up to the ejection nozzle *d* with an ejection opening turned sidewise. Now, according to this invention there is provided on

the discharge pipe *b* at the level A—B or above the same, a lateral chamber *c* which constitutes a kind of collecting space for the rising liquid, the communication being established by small holes *u*, *v* in the wall of the discharge pipe. Two holes of this kind, one of which is arranged in the upper and the other in the lower part, are sufficient for the purpose. It is essential, that the holes are 10 small, so as to interfere as little as possible with the passage of the liquid during the ejection of the extinguishing liquid. In case the liquid rises from any causes during the inoperative position of the apparatus in the 15 pipe *b* and above the level A—B, the chamber *c* will receive the quantity of rising liquid to such an extent, that rising of the liquid as far as the nozzle *d*, that is to say an escape of the liquid, is excluded.

What I claim and desire to secure by Letters Patent of the United States is:—

In a fire extinguisher a discharge pipe within the body of the extinguisher, a hollow metal casing laterally secured to the pipe near the level of the extinguishing liquid, a 25 separating wall between the pipe and said chamber in line with the wall of the pipe, said wall being provided with apertures to establish communication between the pipe and said chamber, substantially as described. 30

In witness whereof I have hereunto signed my name this 7th day of July, 1906, in the presence of two subscribing witnesses.

WILHELM GRAAFF.
